ELECTRIC VAPORIZER

Joseph Robinson, New York, N. Y.

Application October 5, 1948, Serial No. 52,821

4 Claims. (Cl. 219—38)

1

This invention relates to electric vaporizers of the hand type for generating hot, medicated vapors for relieving the distress caused by afflictions of the upper respiratory organs, such as sinusitis, catarrh and the common cold. The present application is a continuation in part of my co-pending applications Serial No. 541,321, filed June 21, 1944, now Patent No. 2,450,444, dated October 5, 1948, and Serial No. 707,289, filed November 1, 1946, now Patent No. 2,462,129, dated February 2, 1949. Among the objects is to provide a simplified "heater, container and applicator unit" which is adapted to sit vertically upright, and which may be removed from its source of electric current and used elsewhere at will. Another object, for electric vaporizers, is to provide an improved heater having terminals constructed to directly receive the slip-plug of a current conducting electric cord, whereby the need for a built in press switch for the vaporizer is eliminated. A still further object is to provide an improved vaporizer which, in addition to providing hot medicated vapors, may be heated and held against the frontal sinus and antrum areas, eyes and nose, for relief of head-aches and other distresses occurring in these regions.

Other objects and novel features of my improvement are described in the following specifications, pointed out in the appended claims and illustrated in the accompanying drawing:

Figure 1 is a vertical section, approximately twice size, through my improved vaporizer;

Figure 2 is a bottom view of the "heater, container and applicator unit" shown in Figure 1, with the adapter plug D removed;

Figure 3 is a plan view of the heater shown in Figure 1;

Figure 4 is a side elevational view of an adapted plug of the present invention;

Figure 5 is a sectional detail showing the heater assembly modified so that the terminal screws 13—14 directly receive a conventional electric cord set having a slip plug E.

Referring to the directions: My improvement comprises the "heater, container and applicator unit" A, a hollow base 1, made of any suitable material, which contains and insulates the heater assembly B and the medicament container C, and a nasal piece 2, the latter being removably mounted, and frictionally held, in an annular seat 2a on the upper end of the base 1. The nasal piece is preferably, but not necessarily, provided with an extension or skirt 3 by which the currents of air that enter the vents 4 on inhalation are directed down into the container C where they

5 entrain the hot vapors and carry them up through the nasal piece 2 into the nasal passage, the currents of air being heated in the journey. The container is secured in the base 1 in any suitable way as by tightly pressing it and its stop or retaining flange 5 into the base, or by molding it in place when the base is formed. The heater B is anchored in the base, preferably out of contact therewith to avoid scorching the base, by a lock washer or retaining device 6, Figures 1 and 2, having one or more prongs 7 that are pressed or crimped rigidly against the inner surfaces of the walls or ribs 8 of the base, Figures 1 and 2. These walls extend substantially below 10 the heater to shield the user from contact with the heater and to dispose the heater well above the surface of any object on which the base may be seated.

15 The heater B includes the usual resistance coil 10, suitably wound in grooves in the upper face of the heater ceramic 11, and insulated with respect to the container C by the mica disc 12.

20 A novel feature of my improved heater lies in equally spacing the screws 13—14 laterally from 25 approximately the vertical center of the heater. This advantageous arrangement is obtained by counter-sinking the head of one or both of the screws until it lies safely below the coil 10, and by passing the lead wire 15 of the inner end of 30 the coil down through the relatively small opening 16, Figure 3, at the center of the ceramic and winding it around the screw 13 and under the terminal 17, the other end of the coil being secured by the screw 14 and in circuit with the 35 terminal 18.

37 As appears in Figures 1 and 2, the terminals 17—18 are counterparts. Each includes a flat laterally extending part or flange 19 by which the terminal is threadingly or otherwise connected to its respective screw 13—14. The flange 19 is turned upwardly at its outer end to form a lug 20 which projects into a slot 21 formed in the side of the ceramic 11 to prevent the terminal rotating on the ceramic into contact with the retaining device 6. The latter is mounted in a closely fitting transverse groove 22 in the bottom of the ceramic to prevent it shifting into contact with the terminals 17—18. Arranging the terminals on the ceramic in this effective manner 45 permits the female and E of a conventional electric cord, Figure 5, or a similar current conducting adapted plug D, Figures 1 and 2, to be slipped over the unthreaded lower portions of the terminals 17—18 to direct current to the coil 50 10, and to be removed therefrom when it is de-

sired to break the circuit. Thus each of the plugs D and E serve as a switch for making and breaking the electric circuit to the vaporizer, and for holding the generated vapors at the desired temperature.

The buyer is not required to purchase, at considerable expense, a special electric cord set when buying my improved vaporizer. A major economy results to him from the novel type of heater and terminal assembly employed wherein a simple adapted plug D is used to connect the "heater, container and applicator unit" to a current source, such as a lamp socket or any extension cord, that may be available. Heating my improved "heater, container and applicator unit" and holding it while hot against the afflicted parts, affords comfort and relief. It is well known that heat is especially effective in alleviating the distresses caused by sinusitus, head-aches, catarrh and the common cold. The heat storing capacity of the heater B, the shape and compactness of the applicator unit A, and the silken quality of its plastic surfaces, while hot, effectively adapts my improvement to this beneficial use.

What I claim is:

1. A heater for an electric vaporizer comprising, in combination, a ceramic base provided with grooves in its upper face, a resistance coil disposed in said grooves, securing devices connected with each end of said coil and extending through said ceramic base, said devices being arranged on opposite sides of the vertical centerline of said base and being approximately equally spaced laterally therefrom, the upper end of one of said devices being buried safely below said coil with the coil passing thereover, and a pair of terminals anchored to said ceramic base by said devices and extending below said base to slidingly receive an electric plug to place said coil in circuit with the source of current and to break such circuit.

2. A heater for an electric vaporizer comprising, in combination, a ceramic base having grooves formed in its upper face, a resistance coil in said grooves, said ceramic having a central opening which extends there-through and having also an outer opening arranged on either side of said central opening and extending through said ceramic, one of said outer openings being larger in diameter at the top than at the bottom, a terminal device in each of said outer openings and having a head portion and a contact portion, the contact portion of both of said terminal devices being disposed below said ceramic and the head portion of one thereof being arranged in the larger diameter of said opening and lying substantially below the bottom of said coil and insulated therefrom by said ceramic, one end of

said coil being anchored directly under the adjacent head of one of said terminal devices and the other end being passed through said central opening into engagement with the other terminal device at a point below the bottom of said ceramic, means for anchoring said terminal devices to said ceramic and said coil to said devices, means for locking said heater in the service position, and means for holding said heater locking means out of contact with said terminal devices.

3. An electric vaporizer for nasal inhalation use comprising an applicator having a hollow base, a container mounted in said hollow base, a removable cover for said container carried by said base and shaped to be received within a nostril opening, a heater also mounted in said hollow base in heat exchanging relation with said container, and terminals arranged directly on said heater to removedly receive the plug of an electric cord or the like source of electrical energy whereby the applicator can be connected to said source of electrical energy to activate the heater and also remove therefrom for use independently of any electrical attachment.

4. An electric vaporizer for nasal inhalation use comprising an applicator having a hollow base, a container mounted in said hollow base, a removable cover for said container carried by said base, shaped to be received within a nostril opening and provided with a central air outlet at the top and air inlets near the bottom, a heater also mounted in said hollow base in heat exchanging relation with said container, terminals arranged directly on said heater, an adapter plug, independent connector means carried by said adapter plug for receiving each of said terminals, terminals arranged on said adapter plug independently connected to said connector means and capable of receiving the plug of an electrical outlet or the like source of electrical energy whereby the applicator can be connected to said source of electrical energy to activate the heater and also removed therefrom for use independently of any electrical attachment.

JOSEPH ROBINSON.
